SAND MULLER
Arthur R. Taccone, 4217 E. Lake Road, Erie, Pa.
Filed May 28, 1963, Ser. No. 283,932
1 Claim. (Cl. 22—89)

This invention relates to sand mullers and, more particularly, to sand mullers for conditioning sand in a foundry.

Sand mullers made according to prior inventions utilized muller wheels which were cylindrical in shape.

It has been discovered that by utilizing sand muller wheels which are oval shaped, the mulling action of the sand will be considerably improved.

It is, accordingly, an object of the present invention to provide an improved sand muller.

Another object of the invention is to provide a sand muller which is simple in construction, economical to manufacture, and simple and efficient to use.

With the above and other objects in view, the present invention consists of the combination and arrangement of parts hereinafter more fully described, illustrated in the accompanying drawing and more particularly pointed out in the appended claim, it being understood that changes may be made in the form, size, proportions, and minor details of construction without departing from the spirit or sacrificing any of the advantages of the invention.

In the drawing:

FIG. 1 is a cross sectional view of a sand muller according to the invention taken on line 1—1 of FIG. 2;

FIG. 2 is a cross sectional side view taken on line 2—2 of FIG. 1; and

FIG. 3 shows two diagrammatic views of the muller with the wheels in two positions of ninety degree rotation from each other.

Now with more particular reference to the drawing, a muller box or container 13 is shown having sides 14 with a mechanism 11 supported thereon for operating a muller axle 12. The muller mechanism 11 shown is similar to that shown in Patent No. 2,377,307. The mechanism rotates the axle 12 around to cause the wheels to mull the sand.

2

The wheels 10 are oval shaped and have a flat periphery that rotates and engages the sand as it swings the axle 12 around the center of the container 13 so that the wheels 10 move over the sand in a circular path. Since the 5 wheels 10 are oval shaped, they will roll over high lumps of sand that would be pushed straight ahead by a round wheel. The major axes of the wheels 10 are about equal in height to the depth of the container 13 and the minor axes are substantially half the major axes.

The foregoing specification sets forth the invention in its preferred practical forms but it is understood that the structure shown is capable of modification within a range of equivalents without departing from the invention which is to be understood is broadly novel as is commensurate with the appended claim.

The embodiments of the invention in which an exclusive property or privilege is claimed are defined as follows:

A sand muller comprising
a muller container to receive sand,
and a muller axle having a wheel on each of its opposite ends,
the intermediate part of said axle being fixed to a mechanism for swinging said axle around a pivot point,
said wheels being non-circular and the length of the major axis of each said wheel being substantially equal to the depth of said container, said wheels being mounted on said axle to roll with said non-circular shape in engagement with said sand,
the length of the minor axis of each said wheel being substantially half said major axis.
